[57] **CLAIM**

The ornamental design for a powder dispenser, substantially as shown and described.

DESCRIPTION

FIG. 1 is a front perspective view of a powder dispenser showing our new design;

FIG. 2 is a front elevational view;

FIG. 3 is a rear elevational view;

FIG. 4 is an elevational view looking from the left of FIG. 1;

FIG. 5 is an elevational view looking from the right of FIG. 1;

FIG. 6 is a top plan view;

FIG. 7 is a bottom plan view; and

FIG. 8 is a fragmentary front perspective view with the dispensing holes in an open position.
